US00D767332S

(12) **United States Design Patent** (10) **Patent No.:** **US D767,332 S**
Strömmер et al. (45) **Date of Patent:** **** Sep. 27, 2016**

(54) **IMPELLER FOR MIXER**

- (71) Applicant: **Outotec (Finland) Oy**, Espoo (FI)
- (72) Inventors: **Ville Strömmер**, Helsinki (FI); **Markus Lehtonen**, Lepsämä (FI); **Tuomas Hirsi**, Helsinki (FI); **Marko Latva-Kokko**, Pori (FI)
- (73) Assignee: **OUTOTEC (FINLAND) OY**, Espoo (FI)

(**) Term: **14 Years**

(21) Appl. No.: **29/526,089**

(22) Filed: **May 6, 2015**

(30) **Foreign Application Priority Data**

(57) **CLAIM**

The ornamental design for an impeller for mixer, as shown and described.

DESCRIPTION

FIG. 1 is a top perspective view of the impeller;
FIG. 2 is a bottom perspective view of the impeller;
FIG. 3 is a top plan view of the impeller;
FIG. 4 is a bottom view of the impeller while inverted;
FIG. 5 is a side view of the impeller;
FIG. 6 is a side view of the impeller; and,
FIG. 7 is a side view of the impeller.
The broken lines shown in the drawings are for illustrative purposes only and form no part of the claimed design.

1 Claim, 7 Drawing Sheets
